US00D786850S

(12) **United States Design Patent** (10) **Patent No.:** **US D786,850 S**
(45) **Date of Patent:** **** May 16, 2017**

(54) **MOBILE PHONE**

(71) Applicant: **Samsung Electronics Co., Ltd.**, Suwon-si (KR)

(72) Inventors: **Jisang Park**, Yongin-si (KR); **Kiseong Kim**, Gwangmyeong-si (KR); **Hongku Yeo**, Seongnam-si (KR); **Jin-Hoo Lee**, Seoul (KR); **Jaewoong Chung**, Seongnam-si (KR); **Duyeong Choi**, Anyang-si (KR); **Minhyouk Lee**, Seongnam-si (KR)

(73) Assignee: **SAMSUNG ELECTRONICS CO., LTD.**, Suwon-si (KR)

(**) Term: **15 Years**

(21) Appl. No.: **29/585,410**

(22) Filed: **Nov. 23, 2016**

Related U.S. Application Data

(63) Continuation of application No. 29/577,843, filed on Sep. 15, 2016, now Pat. No. Des. 782,457.

(30) **Foreign Application Priority Data**

Apr. 14, 2016 (KR) 30-2016-0017737

(51) **LOC (10) Cl.** **14-03**

(57) **CLAIM**

The ornamental design for a mobile phone, as shown and described.

DESCRIPTION

FIG. 1 is a top front perspective view of a mobile phone showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom front perspective view thereof;

FIG. 9 is a bottom rear perspective view thereof;

FIG. 10 is an enlarged view of encircled portion 10 in FIG. 1; and,

FIG. 11 is an enlarged view of encircled portion 11 as illustrated in FIG. 1.

The dashed broken lines in the drawings represent portions of the mobile phone that form no part of the claimed design.

(Continued)

The dot-dash broken lines in the drawings define the boundaries of the claimed design and form no part of the claimed design.

1 Claim, 11 Drawing Sheets
